UNITED STATES PATENT OFFICE

2,379,563

APPARATUS FOR REFINING CRUDE PETROLEUM

Lavoy Carter, Houston, and John T. Barrow, San Antonio, Tex.; said Carter assignor to said Barrow

Application August 7, 1942, Serial No. 454,028

6 Claims. (Cl. 196—2)

This invention relates to apparatus for refining crude petroleum.

An object of the invention is to provide refining apparatus of the character described whereby the hydrogen content of the hydrocarbon will be increased, thus resulting in an increase in the quantity of high octane gasoline produced from a given quantity of the crude petroleum refined.

Another object of the invention is to provide refining apparatus of the character described whereby crude petroleum and water may be emulsified by passing the same through a colloid mill, thus effecting a physical change and thereafter vaporized and subjected to catalytic action whereby the hydrogen content of the petroleum is increased and thereafter effecting a chemical reforming of the hydrocarbon molecules with molecules of water, said chemical reformation being brought about by reason of the disassociation of the atoms of the water molecules and the hydrocarbon molecules and the recombining of these free atoms into reformed hydrocarbon molecules of a richer hydrogen content thus increasing the quantity of high octane gasoline obtainable from the crude petroleum.

The refining process effected by the apparatus results also in the production of butylene from which butadiene, a basic ingredient of synthetic rubber, may be obtained.

With the above and other objects in view, the invention has particular relation to certain novel features of construction, operation and arrangement of parts, an example of which is given in this specification and illustrated in the accompanying drawings, wherein:

Figure 1 shows a diagrammatic plan view of the apparatus.

Figure 2 shows a longitudinal vertical sectional view of the furnace taken on the line 2—2 of Figure 4.

Figure 3 shows a horizontal sectional view.

Figure 4 shows a transverse vertical sectional view taken on the line 4—4 of Figure 3.

Figure 5 shows a side elevational view of the apparatus partly in section.

Figure 6 shows an elevational view of the fractionating tower and associated parts.

Figure 7 shows a fragmentary perspective view thereof.

Figure 8 shows a fragmentary perspective view of the fractionating tower and associated parts, and

Figure 9 shows a horizontal sectional view of

the pump house enclosing the colloid mill and pumps.

Referring now more particularly to the drawings wherein like numerals of reference designate similar parts in each of the figures, the numeral 1 designates a storage tank for the crude petroleum having a supply line 2 and the delivery line 3, the latter being connected into the intake of the pump 4 whereby the crude oil is delivered through the line 5 to the colloid mill 6 of any selected construction.

The numeral 7 designates a water tank which is connected, by the water line 8, into the intake of the pump 9. This pump discharges water through the discharge line 10 into the colloid mill 6. The oil and water are thoroughly emulsified by the colloid mill and discharges therefrom through the discharge line 11, which communicates with a coil 12 in the furnace 13. The discharge line 11 is equipped with an expansion valve 11a, to control the pressure in coil 12.

The emulsion passes through the tubular coil or manifold 12 at a final temperature of about 1400° F.

The manifold 12 terminates in a catalyst case 14 which is filled with a catalyst such as chrome nickel steel wire and thorium oxide. These catalysts cause the chemical reforming of the hydrocarbon molecules with the molecules of water increasing the hydrogen content of the hydrocarbon. Leading from the catalyst case 14, there is an insulated line 15 which enters the top of the heat exchanger 16 which is located near the top of a suitable fractionating tower 17, later to be referred to.

Provision has been made for heating the petroleum emulsion passing through the catalyst case 14. The furnace 13 has been heretofore referred to. It is preferably a brick or masonry furnace and the coil 12 is secured to one side thereof by means of the brackets 18, 18. The inside wall of the furnace opposite the coil 12 is preferably provided with a series of inwardly extended projections 19 formed of radiant material and on opposite sides of the furnace are the series 20, 21 of burner nozzles which project upwardly through the bottom of the furnace and which are spaced apart along the furnace as shown in Figure 3. These burner nozzles are spaced apart and between them are the inwardly projecting partitions 22, 23 formed of brick or other similar material thus providing independent combustion chambers one for each burner nozzle, and causing a more even distribution of heat. The nozzles are connected to manifolds 24, 25 which are sup-

plied with fuel from the fuel pipe 26. The fuel flowing to the manifolds may be controlled by the hand-operated valves 27, 28. Above each nozzle 21 there is an inwardly extended baffle 21a to direct the heat toward the catalyst case 14.

The numeral 29 designates a smoke stack into which the furnace is connected through the flue 30.

As above indicated, the hot gases from the emulsion enter the case of the heater exchanger 16 where said gases are quenched and the temperature is reduced to a proper range which is about 425° F.

Leading from said heat exchanger, there is a pipe 31 which is formed into the branches 31a, 31b controlled by the respective valves 32, 33.

Incorporated into the branches 31a, 31b are the catalyst cases 34, 35 and beneath said cases the branches 31a, 31b unite in a common pipe 36 which enters the tower 17 near the lower end thereof. The branches 31a, 31b beneath the catalyst cases are controlled by the valves 37, 38, respectively, and the common pipe 36 is controlled by a valve 39.

The catalyst cases 34, 35 are filled with copper converting the oxygen compounds formed from the water in the colloid emulsion as a result of the reforming of the hydrocarbon molecules of the crude oil in the colloid emulsion.

There are two catalyst cases at this point so that one or the other of them may be by-passed to permit its cleaning and refilling.

There is a steam pipe 40 which enters the lower end of the tower beneath the connection of the pipe 36 into the tower and which is controlled by the valves 41, 42. This steam prevents flashing of the hydrocarbon as it enters the tower and re-heats and evaporates the hydrocarbon in the tower into a vapor and it passes up through the fractionating tower whose interior construction may be of any approved design. Leading out from the top of the fractionating tower there is a vapor line 43 through which the high fraction vapors pass at approximately 375° F. to a condenser 44. There is a water line 45 leading from any suitable source and formed into a coil within the condenser and connected into said coil and leading out from the condenser there is a water line 46 which enters the heat exchanger 16 and is formed into a coil therein which is connected with the steam pipe 40. Accordingly, the water will be preheated in the coil of the condenser 44 and will pass thence into the coil of the heat exchanger 16 which contains the hot vapors from the emulsion and said water will be converted into steam and will pass on through the line 49 into the bottom of the fractionating tower 17.

As the hydrocarbon vapors rise through the fractionating tower, the lower fractions are condensed by cooling and can be drawn off at different points through relief lines 47, 48 and either re-cycled or transported for storage and some of the higher fractions may be drawn off through the line 49 to be condensed into liquid. These respective lines are controlled by the valves 50, 51, 52. A gas separator 53 has been provided and the gasoline, olefins and hydrogen are delivered from the condenser 44 through the pipe 54 to said oil and gas separator. The olefins and hydrogen are conducted from the separator through the pipe 55 to a gas storage tank such as 56 from which the burner supply pipe 26 leads to the furnace burners. The liquid passes through a conducting pipe 57 to the storage tank 58 for the finished products. The conducting pipe 57 is

equipped with a suitable valve 59 for controlling the flow of the liquid therethrough.

Provision has been made for utilizing a portion of the liquid in the storage tank 58 for refluxing 5 to cool and condense the vapors coming off at the top of the fractionating tower. For this purpose, a line 60 has been provided which leads from the storage tank 58 to a motor driven pump 61 in the pump housing. A portion of this liquid may be 10 delivered, through the deliver line 62, which enters the top of the fractionating tower as shown in Figure 7. Connected into this line, preferably in the pump housing, there is the line 63 through which the liquid not utilized for refluxing may be delivered to a place of storage. The lines 62, 63 15 are provided with the valves 64, 65 through which the flow of liquid through them may be regulated.

The fractions of low boiling point will collect at the bottom of the fractionating tower. A heat exchanger 66 has been provided for the relief of 20 the heavy liquid which collects in the fractionating tower. A relief line 67 leads off from the bottom of the fractionating tower and is connected into the heat exchanger 66 and is controlled by a valve 68. A water line 69 leads from a suitable 25 source and branches into the branch lines 45 and 70, the latter of which enters the heat exchanger 66 and is formed into a coil therein and terminates in a water discharge pipe 71.

Leading from the heat exchanger 66, there is a 30 return line 72 through which the liquid from the heat exchanger 66 may be delivered back to the storage tank 1.

The drawings and description are illustrative 35 merely while the broad principle of the invention will be defined by the appended claims.

What we claim is:

1. Apparatus of the character described comprising means for mixing and emulsifying hydro- 40 carbon and water, means for supplying the water and hydro-carbon, to be mixed to the mixer, means for vaporizing the emulsion, a catalyst in contact with which the vapors from the emulsion are passed, means for maintaining the vapors at 45 high temperature while in contact with the catalyst, a heat exchanger, means for delivering the vapors from the catalyst to the heat exchanger, a fractionating tower, a conduit leading from the heat exchanger and entering the lower portion 50 of said tower, a catalyst in said conduit, means for introducing steam into the bottom of the tower, and means for taking off the vapor from the top of the tower.

2. Apparatus of the character described comprising means for intimately mixing hydro-carbon with water and emulsifying the mixture to cause a mechanical reforming of the molecules 55 of the water and hydro-carbon, means for heating the emulsion to vaporize the same, a catalyst, means for bringing the heated vapors into contact with the catalyst to cause a chemical reforming of the hydro-carbon molecules and water molecules, a heat exchanger for lowering the 60 temperature of the vapors, means to conduct the reformed vapors to the heat exchanger, a fractionating tower, a conduit for conducting the vapors from the heat exchanger into the lower portion of the tower, a catalyst into contact with 65 which the vapors are brought by the conduit as the vapors pass into the tower and whereby the free oxygen is eliminated from the vapors, means for introducing hot steam into the bottom of the 70 tower to re-heat the contents thereof, means for relieving the heavier fractions from the tower and

means for taking off the vapors from the top of the tower.

3. Apparatus of the character described comprising means for intimately mixing hydro-carbon with water and emulsifying the mixture, means for heating the emulsion, to convert the same into vapors, a catalyst, means for bringing the vapors into contact with the catalyst to cause a chemical reforming of the molecules of the hydro-carbon and water to increase the hydrogen content of the hydro-carbon, a fractionating tower, a condenser including a conduit for water, a conduit for vapor leading from the fractionating tower into the condenser, a heat exchanger through which said water conduit passes, means to conduct the reformed vapors to the heat exchanger, a conduit for conducting the vapors from the heat exchanger into the lower portion of the tower, a catalyst into contact with which the vapors are brought as they pass from the heat exchanger into the tower, said conduit for water continuing from the heat exchanger and entering the lower portion of the tower.

4. Apparatus of the character described comprising means for intimately mixing hydro-carbon with water and emulsifying the mixture, means for heating the emulsion, to vaporize the same, a catalyst, means for bringing the heated vapors into contact with the catalyst to cause a chemical reforming of the molecules of the hydro-carbon and water to increase the hydrogen content of the hydro-carbon, a fractionating tower, a condenser including a conduit for water, a conduit for vapor leading from the fractionating tower into the condenser, a heat exchanger through which said water conduit passes, means to conduct the reformed vapors to the heat exchanger, a conduit for conducting the vapors from the heat exchanger into the lower portion of the tower, a catalyst into contact with which the vapors are brought as they pass from the heat exchanger into the tower, said conduit for water continuing from the heat exchanger and entering the lower portion of the tower, a conduit leading from the condenser for conducting the condensed liquid to storage, and a separator incorporated into said last mentioned conduit for separating the liquid from the vapor.

5. Apparatus of the character described comprising means for intimately mixing hydro-carbon with water and emulsifying the mixture, means for heating the emulsion, to convert it into

vapor, a catalyst, means for bringing the heated vapor into contact with the catalyst to cause a chemical reforming of the molecules of the hydro-carbon and water to increase the hydrogen content of the hydro-carbon, a fractionating tower, a condenser including a conduit for water, a conduit for vapor leading from the fractionating tower into the condenser, a heat exchanger through which said water conduit passes, means to conduct the reformed vapor to the heat exchanger, a conduit for conducting the vapor from the heat exchanger into the lower portion of the tower, a catalyst into contact with which the vapor is brought as it passes from the heat exchanger into the tower, said conduit for water continuing from the heat exchanger and entering the lower portion of the tower, a conduit leading from the condenser for conducting the condensed liquid to storage, a separator incorporated into said last mentioned conduit for separating the liquid from the vapor and means for delivering a refluxing liquid into the top of the tower.

6. Apparatus of the character described comprising means for intimately mixing hydro-carbon with water and emulsifying the mixture, means for heating the emulsion, to convert it into vapor, a catalyst, means for bringing the heated vapor into contact with the catalyst to cause a chemical reforming of the molecules of the hydro-carbon and water to increase the hydrogen content of the hydro-carbon, a fractionating tower, a condenser including a conduit for water, a conduit for vapor leading from the fractionating tower into the condenser, a heat exchanger through which said water conduit passes, means to conduct the reformed vapor to the heat exchanger, a conduit for conducting the vapor from the heat exchanger into the lower portion of the tower, a catalyst into contact with which the vapor emulsion is brought as it passes from the heat exchanger into the tower, said conduit for water continuing from the heat exchanger and entering the lower portion of the tower, a conduit leading from the condenser for conducting the condensed liquid to storage, a separator incorporated into said last mentioned conduit for separating the liquid from the vapor and means for relieving the heavier fractions from the bottom of the fractionating tower.

LAVOY CARTER.
JOHN T. BARROW.
